UNITED STATES PATENT OFFICE.

JERVIS R. HARBECK, OF DETROIT, MICHIGAN.

CONTAINER-TOP.

No. 867,500.

Specification of Letters Patent.

Patented Oct. 1, 1907.

Application filed April 6, 1907. Serial No. 366,680.

To all whom it may concern:

Be it known that I, JERVIS R. HARBECK, a citizen of the United States, and a resident at Detroit, in the county of Wayne and State of Michigan, have invented a new and useful Container-Top, of which the following is a specification.

My invention consists in a container head having an opening and a flange projecting inwardly around the opening, in a closure for said opening consisting of a plug or shell of sheet metal having its lower end closed, and in a fibrous gasket secured thereto, the closure extending below said flange so that when the gasket swells, it will engage the lower edge of the flange and thus prevent the closure from coming out.

15 My invention is illustrated in the accompanying drawings, in which

Figure 1 is a view of a cross section of the upper end of a container with three fourths of the closure in position. Fig. 2 is a plan of the head and closure. Fig. 20 3 shows a modified construction of closure.

Similar reference characters refer to like parts throughout the several views.

In the drawings, 1 is the body of a container and 2 the head secured thereto in any desired manner.

25 An opening is formed in the head and a flange 3 bent down as shown in Fig. 1. A bead 4 may be formed just around the flange for the purpose of stiffening the head, if desired. The flange 3 tapers inwardly as shown, the amount of taper however being very slight.

30 The closure for the opening is preferably formed of sheet metal and consists of a shell 5 having its lower end closed by a bottom 6. A flange 7 extends outwardly from the upper edge of the shell and has its outer edge bent inwardly to secure the gasket 8. This

35 gasket 8 is made of fibrous material, strong paper or vegetable parchment preferred, and is drawn to closely fit the closure and is secured thereto by means of the flange 7. Or it may be secured by the "false wire" 9 shown in Fig. 3. The closure and gasket project below the flange 3, and the material of the gasket should be of such strength that it will hold the closure in position because of the "bite" between the lower edge of the flange 3 and the gasket. To insure this engagement between the flange and gasket, the gasket

is usually made of fibrous material adapted to absorb 45 a portion of the contents of the container, when liquid. But for containers for dry or non absorbable materials, the gasket may be formed of a compressible material, in which case, the closure will be forced down to position, compressing the gasket, which will expand or 50 swell when the pressure is relieved and form a ridge just under the edge of the flange. Because of the great changes of atmosphere to which these gaskets are often exposed before they are used, it may be necessary to treat the same so they will not be 55 appreciably affected by changes of temperature or humidity. Where the containers are to be used for substances containing oils that will dissolve paraffin, this substance may be employed. A mixture of glycerin and glue is also valuable, as it protects the gasket 60 from expanding and shrinking, yet does not prevent it from further absorbing the contents of the container. As this mixture remains soft, the gasket will swell below the flange after it has been compressed between the flange 3 and the closure.

65 The amount of taper of the flange 3 and the closure should be the same, and may vary from almost nothing up to five degrees on each side. The advantage of the taper is, that when the closure is put in position, air will be permitted to escape from the container until the closure is almost seated, and excessive air pressure within the container be thus avoided.

Having now explained my improvements, what I claim as my invention and desire to secure by Letters Patent is:—

In a container, the combination of a top provided with an inwardly extending flange, a tapering closure having its lower end closed, the closure when in place extending below the edge of the flange, and a gasket of absorbent fibrous material secured across the closed end and around the shell of the closure, this gasket being adapted to swell by reason of absorbing a portion of the material in the container and to project over the lower edge of the flange of the head and thus securely hold the closure in position.

In testimony whereof, I have signed this specification 85 in the presence of two subscribing witnesses.

JERVIS R. HARBECK.
